OPERATING MEANS FOR FLUORESCENT LAMPS

John Bertram, Rugby, England, assignor to General Electric Company, a corporation of New York

Application May 7, 1941, Serial No. 392,386
In Great Britain May 21, 1940

10 Claims. (Cl. 315—98)

This invention relates to lamp holders and to an associated electrical starting circuit for double-ended electric discharge lamps, for example, fluorescent lamps of the type now in commercial use.

Such lamps are frequently started by means of a resonant circuit which may include a choke transformer and capacitor in series for supplying current to a pair of secondary windings connected to the heating cathodes at each end of the lamp. This arrangement is such that a resonant circuit is formed by the capacitor and choke transformer to provide a higher initial current heating the cathodes rapidly so that the lamp will operate very quickly after being connected to the source of current supply. In normal operation, this relatively heavy current of the resonant circuit is applied to the lamp only during the starting period since it is cut off by the shunt path provided by the arc which is struck to light the lamp. In case of failure of the lamp, the shunt path is broken causing re-establishment of the resonant circuit. Upon replacement of the lamp in case of failure, it is desirable to destroy the resonant circuit to prevent the heavy current from damaging the associated electrical apparatus or injuring a careless workman replacing the lamp. It is further advantageous to break the resonant circuit automatically by removal of the lamp from the associated lamp holder rather than through the provision of a separate switching means. To this end, one of the lamp holders is provided with a switching means operable upon removal of the lamp to interrupt the resonant circuit. In this case the switching means operates to disconnect the condenser from its series relationship with the choke transformer thereby causing an interruption of the resonant circuit through these elements.

It is an object of the invention to provide a holder for an electric discharge lamp of the type described so constructed and arranged that the associated resonant circuit from which the lamp is operated will be disrupted upon removal of the lamp from the holder.

It is another object of the invention to provide an improved operating mechanism for an electric discharge lamp which employs a resonant circuit in which the resonant circuit is destroyed automatically by removal of the lamp from the associated holder.

It is a further object of the invention to provide an improved lamp holder of the type described which includes a switching mechanism operated by movement of the lamp within the holder.

In the accompanying drawing, Fig. 1 is a sectional view through the holder taken along the line 1—1 of Fig. 2 and showing the lamp pins

in seated engagement with the contacts of the lamp holder; Fig. 2 is a side view of the holder, partly in section, showing an electric discharge lamp mounted in position; Fig. 3 is a view of the switching mechanism of the holder taken along the line 3—3 of Fig. 2; Fig. 4 is a diagrammatic showing of the resonant circuit for operating the lamp and illustrates the manner in which the switching mechanism of the lamp holder is connected into the circuit; and Fig. 5 is a perspective view of the end ferrule of the lamp.

Referring to the drawing, there is shown a tubular electric discharge lamp 10, for example, a fluorescent lamp of the type now in commercial use, each end of the lamp being provided with a ferrule 11 carrying spaced contact members or prongs 12. As shown by Fig. 5, the ferrule is provided with a spacer element 13 of insulating material which is disposed between the contact prongs 12 and which is provided with an enlarged outer end or extension 14 carrying a shorting or conducting member 15 for a purpose to be described later.

The lamp holder for mounting the lamp is constructed in two parts, designated part 1 and part 2, which are shown individually by Figs. 3 and 1 respectively, while the assembled lamp holder is shown by Fig. 2. In the assembled position of parts 1 and 2 shown by Fig. 2, the parts are mounted back to back and are separated by means of a plate of insulating material 16 which spaces the parts from one another; the parts are held together with the plate 16 by any suitable fastening means such as rivets (not shown).

Turning now to a consideration of the construction of part 2 and referring particularly to Fig. 1, this part is formed with a body or housing of insulating material 16 having a chamber 17 provided with a slot 18 extending to an outer edge of the housing and having a width smaller than the spacing of the prongs 12. In chamber 17 are two spaced contact members 19 and 20 adapted to cooperate with the contact prongs of the tubular lamp; the contact members are provided with extensions seated in the spaced channels 21 formed in the housing 16 and the ends of the contact members are provided with angularly extending terminal portions 22 which rest in recesses 23 formed in the base of the housing. A terminal screw 24 is mounted in the terminal portion of each of the contact members for wiring the lamp holder to a source of current. The contact members 19 and 20 are formed of flexible material such as spring bronze and they are normally located in the plane of an opening 25 formed of the front edge of the lamp holder which merges with the slot 18. This means that the contact pins of the lamp may be moved in a straight line downwardly

through the slot 18 and thereafter rotated within the opening 25 to bring them into engagement with the contact members, this position being shown by Fig. 1.

Part 1 of the lamp holder is likewise formed with a housing of insulating material 26 which is provided with an enlarged recess 27 at one end for receiving the spaced contact members 28 and 29. These members are formed of flexible material, such as spring bronze, and are provided with extending portions seated within the channels 30 formed in the housing 26; they are likewise formed with laterally extending terminal portions 31 seated within recesses 32 in the base of the housing and cooperating with terminal screws 33 for connection with the electrical circuit. A slot 34 of a width smaller than the length of the shorting or switch member 15 is formed at the upper portion of the housing 26 and extends from the chamber 27 to the outer edge of the housing; this slot receives the outer end of the spacer member 14 formed on the end ferrule of the lamp. The spacer member 14 passes through this slot upon mounting the lamp in the holder and as the lamp is rotated to bring the contact prongs into engagement with the contact members 19 and 20 of the socket, the spacer 14 is likewise rotated to bring the shorting member 15 into engagement with the spaced contact members 28 and 29. This is the position shown by Fig. 3.

When the parts 1 and 2 are placed back to back on each side of the insulating spacer 3, the pairs of contact blades 19 and 20 and 28 and 29 are spaced from each other laterally and a restricted opening 35 is formed in the insulating separator member 3. The upper end of the opening 35 is extended to form a slot 36 extending to the outer edges of the member so that upon insertion of the lamp the spacer 13 will pass downwardly through the slot 36 and rotate within the opening 35, but the opening 35 is of smaller diameter than that necessary to receive the end extension 14 of the spacer member so that this extension is maintained within the chamber 27 and cannot be pulled transversely of the socket to bring the shorting member 15 in contact with the contact members 19 and 20.

A two part lamp holder of the type described is used as one of the lamp holders to support one end of the lamp in those cases where the lamp is to be operated by means of a resonant circuit. An arrangement of this type is shown by Fig. 4. The right-hand end of the lamp is provided with a two part lamp holder of the type already described, while the left-hand end of the lamp is provided with a one part holder similar to that shown by Fig. 1 of the drawing, in which only the contact members 19 and 20 are provided for cooperation with the contact prongs 12 of the lamp. The lamp is wired according to the circuit arrangement shown by Fig. 4.

With the lamp in mounted position, current from the supply lines 37 and 38 flows to a choke transformer 39 having a pair of secondary windings 40. Each secondary winding is connected to a corresponding cathode at the end of the lamp by means of supply lines 41 and 42 connected to the contact members 19 and 20 of the lamp holder so that current is fed to the cathodes through the connector prongs 12 on the ends of the lamp. The current path through the choke transformer is from the supply line 37 through the transformer, line 44 to the contact member 28 and

thence across the shorting member 15 to the other contact member 29 and thence through line 45 to a capacitor 46 to the other supply line 38. The condenser 46 is of such capacity as to form with the choke transformer 39 a resonant circuit so that initially a large flow of current takes place through the transformer primary. The resulting voltage of the secondary windings 40 effects a rapid heating action of the cathodes 43 at opposite ends of the lamp. This is of advantage in that it increases the speed with which the lamp starts after the operating switch has been turned on. As soon as the cathodes 43 have been heated sufficiently, an arc strikes between the cathodes thereby lighting the lamp. This arc forms a shunt path across the capacitor whereby the circuit of the transformer 39 no longer resonates. Current now flows from the supply line 37 to the transformer 39, line 44, contact 20 to the right-hand cathode 43, thence across the arc path to the left-hand cathode, a corresponding contact member 20 of the lamp holder, a line 47 to the other supply line 38. A choke coil 48 is inserted in the lead 47 to limit the flow of current through the lamp.

As long as the lamp is operating it provides a short circuiting path around the capacitor, hence the circuit formed by the capacitor 46 and the transformer 39 no longer resonates so that there is no danger of excessive current voltages across either nor is there any danger to the other associated apparatus. In the event that the lamp fails, then this short-circuiting path is interrupted and the high intensity resonant current is again built up in the resonant circuit. During removal of the lamp 10 the interruption of the high intensity current might be injurious to the associated apparatus or even to the workman replacing the lamp were it not for the fact that the shorting member 15 must be rotated upon removal of the lamp to open the circuit across the contact members 28 and 29 thereby cutting out the condenser 46 and breaking down the resonant circuit through this element and the choke transformer 39. By providing the shorting member 15 on the end ferrule of the lamp, it will be apparent that it is unnecessary to employ separate switching means to break the resonant circuit. While the operating means for controlling the circuit across the contact members 28 and 29 has been shown as incorporated on the end ferrule of the lamp, it should be obvious that the specific switching arrangement shown might be replaced by one in which the contacts are opened and closed by engagement with other portions of the lamp so long as the switching arrangement is operated by rotation of the lamp within the lamp holder or upon removal of the lamp from the holder.

What I claim as new and desire to secure by Letters Patent of the United States is:

1. In combination with a tubular lamp provided with a ferrule having spaced contact prongs, means for connecting and starting the lamp including a socket having a two-part housing, one part of said housing being provided with a recess in a face thereof and extending to an outer edge of said housing, spaced contact blades in said recess, the other part of said housing being provided with a second recess, switch contact members in said second recess, switch operating means carried by one of the lamp ferrules, the lamp being mounted on said socket by straight line movement of the lamp prongs transversely to the axis of the lamp through the outer

portions of said recesses and in direction of a plane through the prongs and subsequent rotation of the prongs to bring them into engagement with the spaced contact blades and simultaneously causing said switch operating means to operate said switch contact members.

2. In combination with a lamp having spaced contact prongs, a housing provided with a recess in a face and extending to an outer edge thereof, spaced contact members in said recess, said recess having a width in the outer edge smaller than the spacing of the prongs to require upon assembly movement of the lamp prongs in alignment transversely to the axis of the lamp into said recess and rotation into engagement with said spaced contact members upon seating the lamp in said socket, and separate switch means mounted on said socket and being operated upon rotation of the lamp to control the circuit to the lamp.

3. In combination with a lamp having spaced contact prongs, a housing provided with a recess in a face and extending to an outer edge thereof, spaced contact blades in said recess, said housing being provided with a second recess, relatively movable contact members disposed into said recess, the lamp prongs being moved in alignment transversely to the axis of the lamp into said recess and rotated into engagement with said spaced contact members upon seating the lamp in said socket, and means for operating said movable contact members in response to rotation of the lamp in said socket.

4. In combination with a double-ended discharge lamp having a cathode at each end connected to spaced contact prongs, a socket at each end of the lamp, each socket being provided with a recess in a face extending to an edge thereof and spaced contact members in said recess, switch mechanism separate from said contact members carried by one of said sockets, said switch mechanism being controlled by movement of the lamp in said one socket and a source of potential including a resonant circuit connected to said contact members for energizing said cathodes, said resonant circuit including said switch mechanism, said resonant circuit being broken by opening of said switch mechanism upon movement of the lamp in said one socket.

5. In combination with a double-ended discharge lamp having a cathode at each end connected to spaced contact prongs, a socket at each end of the lamp, each socket being provided with spaced contact members for engaging the lamp contact prongs, one of said sockets being provided with a switch mechanism separate from said contact members and controlled by movement of the lamp in said one socket, a source of potential, a resonant circuit comprising a transformer and a capacitor connected in series with said switch mechanism and said source of potential, the secondaries of said transformer being electrically connected to the contact members each of said sockets for energizing the cathodes, said resonant circuit being broken upon opening of said switch mechanism upon movement of the lamp in said one socket.

6. In combination with a discharge lamp having a ferrule with two prongs, a combined switch and socket for connecting the lamp to a source of supply and for simultaneously closing a resonant circuit, said switch and socket having a

back part with a recess, two contact members positioned in the recess and a front part with another recess and two contacts positioned in the last mentioned recess for cooperation with the prongs, a switch member supported on the ferrule and axially spaced from the prongs for connecting the contact members, said switch member having a length greater than the spacing of the prongs to preclude insertion of the lamp into the socket by axial movement of the lamp, the aforementioned recesses having an extension forming a slot through which the prongs and switch member are moved during assembly and dismantling, the width of the slot being smaller than the spacing of the prongs to require turning movement of the lamp about its axis prior to removal of the lamp from the socket.

7. A socket comprising a rear casing half with a recess and two spaced contact members mounted therein, a front casing half having a recess with two other contact members mounted therein, each recess being extended through the respective casing half to form slots of different widths smaller than the spacing of the respective contact members.

8. A socket comprising a housing having front and back portions, and two pairs of contacts mounted in the front and back portions respectively with the contacts of each pair symmetrically spaced from a central plane through the housing, the spacing of the contacts in the back portion being greater than that of the contacts in the front portion, the front and top of the housing forming an opening having its largest dimension across the top of the back portion, the dimensions of the opening in the planes of the two pairs of contacts being smaller than the spacing of the respective pairs of contacts.

9. A socket for a discharge lamp having a ferrule with spaced contact prongs and a switch for closing a resonant circuit for such lamp, said socket comprising a housing, two pairs of spaced contacts held in the housing for cooperation with such prongs and switch respectively, one pair of contacts being located back of the other pair and spaced more than the latter, the front and top of the housing forming a slot of a shape and width requiring lateral insertion of the prongs and switch with the prongs in alignment and requiring subsequent to such insertion rotational movement of such lamp to effect engagement of the prongs and the switch with the respective contacts.

10. A socket for a discharge lamp having a ferrule with spaced contact prongs and a switch, said socket comprising a housing having a front portion with two spaced contacts mounted therein and a back portion with two other contacts mounted therein for cooperation with such switch and spaced more than the contacts in the front portion, the top and front of the housing forming an opening through which such prongs and switch may be inserted only laterally when in alignment, the slot in the front and back portions of the housing being narrower than the spacing of the respective contacts therein to require rotational movement of such lamp subsequent to insertion of the prongs and switch through the opening and prior to removal through the slot.

JOHN BERTRAM.
